UNITED STATES PATENT OFFICE.

GEORGE R. HUDSON, OF SUPERIOR, NEBRASKA.

RAILWAY-CROSSING SIGNAL.

Application filed May 26, 1925. Serial No. 32,979.

To all whom it may concern:

Be it known that I, GEORGE R. HUDSON, a citizen of the United States, residing at Superior, in the county of Nuckolls and State of Nebraska, have invented certain new and useful Improvements in a Railway-Crossing Signal, of which the following is a specification.

This invention relates to improvements in railway crossing signals, and has for its principal object to provide a visual signal which is arranged preferably at the intersection of a highway with the rails of a railroad for the purpose of warning of an approaching train.

One of the important objects of the present invention is to provide a railway signal which will be automatically actuated by the approach of a train, the signal being moved to an inoperative position by the train after the same has passed the grade crossing.

A further object of the invention is to provide an automatic signal for grade crossings of the above mentioned character which will at all times be positive and efficient in its operation, the signal in no way interfering with the passing of vehicles over the rails at the crossing when in an inoperative position, nor affecting the traveling of a train over the rails.

A still further object is to provide a railway crossing signal of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawings forming a part of this application, and in which like numerals designate like parts throughout the same:

Figure 1 is a top plan view of the signal embodying my invention showing the manner in which the same is associated with the rails, and intersecting highway.

Figure 2 is a side elevation thereof, the signal being disposed in its normal inoperative position.

Figure 3 is a similar view showing the arrangement of the parts when the signal is in an operative position.

Figure 4 is a fragmentary side elevation of one of the trip members.

Figure 5 is a vertical sectional view therethrough, and

Figure 6 is a detail perspective view of the latch forming a part of the present invention.

In the drawings wherein for the purpose of illustration is shown the preferred embodiment of my invention, the numerals 1 and 2 designate a pair of supporting standards which are arranged on opposite sides of a grade crossing A adjacent the rails B, the standards being preferably located a suitable distance from the grade crossing. A block 3 is supported below the rails B in any suitable manner, and is located at the central or intermediate portion of the highway adjacent the rails in a manner as clearly illustrated in Figure 1.

The visual signal comprises a suitable metallic plate 4, the same being pivotally secured on the outer face of the block 3, as illustrated at 5. The pivot is preferably arranged eccentrically of the plate, and this feature is more particularly, and clearly shown in Figures 2 and 3 of the drawings. The plate 4 which comprises the visual signal member is provided with a centrally located slot 6, and the purpose thereof will hereinafter be more fully described. One of the sides of the plate 4 is bent to provide a lip 7, said lip being formed adjacent the slot 6, and the purpose of this lip will also hereinafter be more fully described. The plate 4 is of such size as to enable the same to be readily visible by a vehicle which is traveling on the highway and about to approach the grade crossing A, when the signal member is disposed in an operative position.

A pair of trip members designated generally by the numerals 8 and 9 are associated with the supporting standards 1 and 2 respectively, and each of the aforementioned trip members include the complementary arms 10 and 11, each of which is formed of a single piece of sheet metal which is folded along its longitudinal center. The upper portion of the lower arm 10 of each of the trip members is cut away at its back as illustrated at 12, so that the upper complementary arm 11 may swing rearwardly on its pivot 13 so as to prevent the breaking of the tip should the train move in a direction 105

reverse from that in which the trips are adapted to swing.

The pivot 13 which provides a connection for the complementary arms of each of the trip members also provides a means whereby the respective trip members are pivotally supported on the inner sides of the standards, the trip 8 being pivotally supported on the standard 1 while the trip 9 is similarly supported on the standard 2. As is clearly illustrated in Figure 5, the pivot is in the form of an elongated bolt which has a nut 14 threaded on the threaded end thereof so that the complementary arms of each of the trip members may be readily assembled or disassembled. An axial coil spring 15 is associated with the pivot bolt 13 of each of the trip members and cooperates with the complementary arms for normally maintaining the same in vertical alignment with each other, the arms of end portions of the coil spring engaging the respective complementary arms of the trips as is illustrated at 16. A wheel 17 is rotatably supported in the upper end of the upper arm 11 of each of the trip members, and the purpose thereof will be presently apparent.

An elongated piece of wire 18 is secured at one end to one end of the plate 4, as at 19, the other end of the wire being secured to the transversely extending pin 20 which is carried by the lower arm 10 of the trip member 8.

An angularly shaped latch 21 is pivotally supported intermediate its ends on the top of the block 3 as at 22. One of the arms of the angularly shaped latch 21 terminates in the lateral extension 23, the end of which is beveled as illustrated at 24 for cooperation with the lip 7 formed in the side of the plate 4 and for further cooperation with the slot 6. The other arm of the angularly shaped latch 21 is attached to a wire 25, the other end of the wire cable extending over a pulley 26 which is secured on the inner side of the standard 2 adjacent the lower end of the lowermost arm of the trip member 9 and the end of this wire cable is secured to a transversely extending pin 27 which is supported by the lower portion of the lowermost arm 10 of the trip member 9.

A coil spring 28 is associated with the lowermost arm of the trip member 9 for normally holding the same in its vertical position, and the other trip member 8 is normally maintained in a vertical position through the medium of the coil spring 29 which is secured at one end to the lower end of the standard 2 and more particularly to the laterally extending bar 30 associated with the standard, the other end of the coil spring being secured to a rod 31, the other end of the rod being connected to the pivoted plate 4 at the connection 19 which is provided for one end of the wire 18. Suit-

able transversely extending stop pins 32 and 33 respectively are associated with the standards 1 and 2 for limiting the swinging movement of the respective trip members in one direction.

The angularly shaped latch 21 is normally maintained in the position shown in Figure 1 of the drawings through the medium of the coil springs 34, a stop pin 35 extending upwardly from the top of the block 3 and cooperating with the lateral extension 23 of the angularly shaped latch 21 for limiting the swinging movement thereof in one direction.

Normally, the parts are arranged as shown in Figure 2 of the drawings, and the signal member 4 is disposed in an inoperative position entirely out of view. As the train approaches the grade crossing A, traveling in one direction, the wheel 17 which is supported in the upper end of the uppermost arm of the trip member 8 will be engaged by suitable trip engaging member 36 which is carried by the train and depends therefrom, the same being located in such a manner as to at all times be disposed in a position for engagement with the wheels of the trip members. As the member 36 travels over the wheel 17, the trip member 8 will be swung forwardly causing the signal member 4 to swing upwardly on its pivot 5 against the tension of the coil spring 29, and as soon as the slot 6 is disposed directly opposite the latch 21, the end of the lateral extension 23 formed on one of the arms of the latch will enter the slot, and thereby hold the signal member 4 in a vertical position so that the same will project above the rails and be disposed substantially in the central portion of the highway so that persons approaching the grade crossing will readily see the signal, and thus be warned of the approaching of a train.

After the train has passed over the grade crossing, and the member 36 engages the wheel 17 carried by the upper end of the uppermost arm of the other trip member 9, the latter will swing in a forward direction on its pivot, causing a forward pull to be exerted on the wire cable 25, and as the latter is connected to the inner end of the pivoted latch 21, the latch will be caused to swing on its pivot so that the beveled end 24 of the lateral extension 23 which extends into the slot 6 will be brought out of engagement with the slot, and the spring 29 together with the rod 31 will automatically return the signal member 4 and the trip member 8 to their normal positions, the positions of the signal member and the trip member 8 when the signal is disposed in an operative position, being clearly illustrated in Figure 3. The spring 28 and the spring 34 will return the trip member 9 and the latch 21 respectively to their normal posi-

tions when the train has passed over the wheel of the trip member 9, thus refitting the trip and the signal, as well as the latch so as to enable other trains to actuate the 5 signal in the same manner.

As heretofore stated, by constructing the trip members as described, the same will be prevented from becoming broken and rendering the signal inoperative should a train 10 engage the trip members when traveling in a direction reverse from that heretofore described.

It will thus be seen from the foregoing description, that a railway crossing signal has 15 been provided which will be automatic in its operation, and will furthermore at all times be positive and efficient in carrying out the purposes for which it is designed. The simplicity in which the present device is constructed furthermore enables the same to be 20 installed at a grade crossing without affecting or interfering with the movement of trains or vehicles over the crossing.

While I have shown the preferred embodiment of my invention, it is to be understood that minor changes in the size, shape, and arrangement of parts may be resorted to without departing from the spirit of the invention and the scope of the appended 30 claims.

Having thus described the invention, what I claim as new and desire to secure by Letters Patent is:—

1. An automatic railway signal for grade 35 crossings comprising in combination, a pivoted signal member supported adjacent the grade crossing, said signal member being provided with a slot, means for moving the signal member to an operative position, a latch cooperating with said slot for holding the signal member in said operative position, and means for effecting the return of the signal member to its normal inoperative position.

45 2. An automatic railway signal for grade crossings comprising in combination, a pivoted signal member supported adjacent the grade crossings, said signal member being provided with a slot, means for moving the signal member to an operative position, a latch cooperating with said slot for holding the signal member in said operative position, means for releasing the latch, and means for simultaneously effecting the return of the signal member to its normal inoperative position when the latch is released.

3. An automatic railway signal for grade 60 crossings comprising in combination, a pivoted signal member supported adjacent the grade crossing, said pivot being eccentrically associated with the signal member, a pair of trip members supported on opposite sides of the grade crossing, one of said trip members being connected to said signal member for moving the same to an operative position

when the trip member is actuated by a train approaching the grade crossing, a latch for holding the signal member in an operative position, a connection between said latch and the other trip member, said latch adapted to 70 be disengaged from the signal member when the last mentioned trip member is actuated by the train, and means for effecting the return of the signal member and the first mentioned trip member to their normal positions. 75

4. An automatic railway signal for grade crossings comprising in combination, a pivoted signal member supported adjacent the grade crossing, said pivot being eccentrically associated with the signal member, a pair of trip members supported on opposite sides of the grade crossing, one of said trip members being connected to said signal member for moving the same to an operative 80 position when the trip member is actuated by a train approaching the grade crossing, a latch for holding the signal member in an operative position, a connection between said latch and the other trip member, said latch adapted to be disengaged from the signal member when the last mentioned trip member is actuated by the train, means for effecting the return of the signal member and the first mentioned trip member to their normal 85 positions, an additional means for returning the latch and the second trip member to their normal positions.

5. An automatic railway signal for grade crossings comprising in combination, an eccentrically pivoted signal member supported adjacent the grade crossing, a pair of trip members supported on opposite sides of the grade crossing, a connection between one of the trip members, and the signal member, whereby the same may be moved to an operative position when said trip member is actuated by a train approaching the grade crossing when traveling in one direction, said signal member being provided with a slot, a pivoted latch cooperating therewith for holding the signal member in an operative position, means for connecting the latch to the other trip member whereby said latch is disengaged from the slot when the last mentioned trip member is actuated by the train passing thereover, and resilient means for effecting the return of the signal member and the first mentioned trip member to their 100 normal positions. 110

6. An automatic railway signal for grade crossings comprising in combination, an eccentrically pivoted signal member supported adjacent the grade crossing, said signal member being provided with a slot, a pair of supporting standards arranged on opposite sides of the grade crossing, a pair of trip members pivotally supported on the respective standards, a connection between one of the pivoted trip members and said signal 115 120 125 130

member whereby the signal member is moved to an operative position when a train actuates the pivoted trip member when traveling in one direction, a pivoted latch cooperating with the slot for holding the signal member in its operative position, a connection between the pivoted latch, and the other pivoted trip member for releasing the latch from engagement with the slot when the

train passes over the last mentioned trip member, and means for effecting the return of the signal member to its normal inoperative position after the latch has been disengaged from the slot in the signal member.

In testimony whereof I affix my signature.

GEORGE R. HUDSON.
